ABRADING MACHINES

Oscar W. Dillon, Sturbridge, Mass., assignor to American Optical Company, Southbridge, Mass., a voluntary association of Massachusetts

Application April 14, 1953, Serial No. 348,710

1 Claim. (Cl. 51—124)

This invention relates to surfacing devices and more particularly to hand surfacing machines such as are used in the ophthalmic industry in surfacing lenses or similar articles.

One of the principal objects of the invention is to provide a machine of the above character with novel and efficient means for varying the speed of rotation of the abrading tool.

Another object is to provide a hand surfacing machine having a motor driven surfacing tool and readily accessible manually operable means for energizing and de-energizing the motor as desired.

Another object is to provide means for varying the speed of rotation of the abrading tool which is preferably operable when the machine is in motion.

Another object is to provide a machine of the above character wherein the tool supporting spindle, the tool on said spindle and the abrasive pan are all disposed in axially aligned relation with each other and are tilted forwardly to facilitate greater ease to the operator in performing the abrading operation and to cause the abrasive used during said abrading operation to collect in the front of the abrading tool whereby it is more readily accessible to the operator.

Other objects and advantages of this invention will become apparent from the following description taken in connection with the accompanying drawings and it will be apparent that many changes may be made in the details of construction and arrangement of parts without departing from the spirit of the invention as expressed in the accompanying claim. I, therefore, do not wish to be limited to the exact details of construction and arrangement of parts shown and described as the preferred form only has been given by way of illustration.

Referring to the drawings:

Fig. 1 is a top plan view of the device embodying the invention;

Fig. 2 is an enlarged side elevational view of said device shown partially in section;

Fig. 3 is an enlarged fragmentary sectional view taken as on line 3—3 of Fig. 1 and looking in the direction indicated by the arrows; and

Fig. 4 is a fragmentary side view of the motor driven pulley showing a portion thereof in section.

Referring more particularly to the drawings wherein like characters of reference designate like parts throughout various views, the device embodying the invention comprises a base 6 having an attachment seat 7, adjacent the rear thereof, provided with a web 8 having a central opening 9 therein to which is secured a motor 10 by bolts or other similar means 11. The motor 10 has a shaft 12 which extends internally of the base and on which is mounted an expansion pulley 13. The pulley 13 has a stationary part 14 having an inner cone-shaped side surface 15 and a movable part 16 also having an inner cone-shaped surface 17. The movable part 16 is mounted to slide longitudinally of the shaft 12 and is

2

restricted in its movement by a coil spring 18 carried by the shaft. The coil spring is interposed between a flange 19 mounted on the end of the shaft 12 and the outer central side surface of the movable member 16. A housing 20 is provided on said member 16 in overlying relation with the coil spring 18 and in sliding engagement with the flanged end 19 of the shaft.

The pulley 13 is connected with a pulley 21 mounted on the lower end of a spindle 22 through a belt 23. The belt 23 has a wedge-shaped cross section for engaging the respective inner cone-shaped surfaces of the portions 14 and 16 of the pulley 13 and for engaging a tapered circumferential channel 24 formed in the face of the pulley 21. The pulley 21 is secured to the spindle 22 by a set screw or the like 25. The spindle 22 is mounted within a pair of spaced bearings 26 and 27 and has a tapered upper end 28 adapted to detachably receive an abrading tool or lap 29. The bearings 26 and 27 are carried by a supporting member 30 secured, as by bolts or the like 31, to a plate 32. The plate 32 rests on a pair of angularly disposed slide plates 33 secured to the upper wall 34 of the base 6 by screws or the like 35. The upper wall 34 is provided with an opening 36 through which the spindle and bearing support 30 extends.

The plate 32 is pivotally connected at 37 to the upper wall 34 of the base 6 as shown best in Fig. 1. The plate 32 further has a block 38 secured thereto as by screws or the like 39. The block 38 is adjustably secured to a tie rod 40 by a ball and socket connection 41. The tie rod 40 is secured to a crank lever 42 by a ball and socket connection 43 similar to the connection 41. The crank lever 42 is connected to a shaft 44 rotatably supported in a bearing 45 in the side wall of the base 6. A hand lever 46 is attached to the outer end of the shaft 44 to provide manually operable means for rocking the crank lever. The bearing 45 is secured to the side wall of the housing by screws or the like 47.

The plate 32 has a rim 48 secured throughout the contour edge thereof and said plate has a cylindrically shaped housing 49 secured thereto by screws or the like 50. The housing 49 has an inwardly turned upper edge portion 51 to provide an inwardly disposed lip for supporting the upper rim portion 52 of an abrading pan 53. The abrading pan 53 has a central upwardly disposed tubular portion 54 fitted about the shank 55 of a tool or lap 29 and lying beneath said tool or lap. The rim 48 is provided with an upwardly extending bearing portion 56 in which is slidably mounted a sleeve 57 having a flange portion 58 on the upper end thereof. The sleeve 57 may be raised or lowered in the bearing 56 and is held in adjusted position by a clamp screw 59. Inwardly of the sleeve 57 there is rotatably mounted a spindle 60 having its upper end attached inwardly of the neck 61 of a yoke 62 by a pin or the like 63. The spindle has its lower end threaded to receive a nut 64 which is adapted to prevent longitudinal movement of the spindle relative to the sleeve 57 while permitting rotation thereof. The yoke 62 has a split collar 65 pivotally attached thereto, as illustrated at 66. The split collar 65 slidably receives a manually operable lever 67 which may be adjusted longitudinally of said collar and held in desired position of adjustment by a clamp screw 68. The lever 67 has a longitudinal bore 69 through which there is extended wires 70 connected adjacent one end thereof to a trigger type switch 71 carried by a handle 72 mounted on the free end of the lever 67. The wires 70 are connected to the motor 10 and also to a suitable source of electrical energy, as by the lead 70a, whereby the turning off or on of said switch 71 will energize or de-energize the motor 10.

The lever 67 has a perforated block 73 secured thereto

intermediate its ends. The block 73 has a lens block pin 74 extending therethrough, as shown by Fig. 2. The pin 74 has a recessed flattened side 75 adapted to be engaged by a clamp screw 76 whereby the pin may be raised or lowered relative to said block and secured in adjusted position by said clamp screw. The lower end of the pin has a tapered tip 77 secured thereto and adapted to engage with the tapered socket 78 of a lens block 79. The lens block 79 has a lens blank 80 to be abraded secured thereto by a layer of pitch or other suitable adhesive 81.

The lever 67, block 73, and handle 72 are preferably formed of a heavy metal and are so dimensioned as to introduce substantially the weight desired to be exerted on the lens blank during the abrading operation, however, the operator may increase the pressure on the lens blank by exerting manual pressure on the lever.

The motor 10, between it and the web 8, is provided with suitable cushioning means 82, such as a layer of synthetic rubber or other suitable means.

As shown in Figs. 1 and 2, the axes of the spindle 22, lap 29 and pan 53 are in substantially concentric relation with each other and are all tilted forwardly so as to cause the pan 53 to angle forwardly and downwardly whereby the abrasive used during the abrading of the lens blank 80 will settle, in the forward end of the pan 53 under the action of gravity, at a location forwardly of the lap 29 as diagrammatically illustrated at 83. This arrangement further aids the operator, during the abrading of the lens blank, as it permits more of a plan view of the lap 29 and the relation of the lens blank therewith during the abrading operation and which is under the manual control of the operator.

The split pulley 13 and pivotal connection of the plate 32 with the upper wall 34 of the base 6 is to enable changing the speed of rotation of the tool or lap supporting spindle 22. This is accomplished by first energizing the motor 10 by manipulation of the switch 71 whereby the pulley 13 will be rotated and will, in turn, rotate the pulley 21 through the belt connection 23. When the plate 32 and the associated parts of the device carried thereby is adjusted about the pivot 37 by proper manipulation of the lever 46 to the rearmost position, as shown in full lines in Fig. 1, the pulley 13 will be functioning effectively at its maximum diameter as shown by the related position of the belt 23 with said pulley in Fig. 2. The speed of the motor and the related diameters of the respective pulleys 13 and 21 are so controlled that when the device is adjusted, as shown in Fig. 2, the speed of the spindle 22 will be approximately 875 R. P. M. However, if it is desired to reduce the speed of rotation of the spindle 22, the lever 46 may be pulled in a forward direction. When moved to this position, the crank lever 42 and the link connection 40 thereof with the block 38 on the plate 32 will cause said plate and the associated parts of the device carried thereby to be swung forwardly about the pivot 37 to a position as indicated by the dash line 84 in Fig. 1. This will exert a pull on the belt 23 of an amount sufficient to cause the portions 14 and 16 of the split pulley 13 to spread relative to each other against the resilient action of the coil spring 18, as shown in Fig. 4, whereby the effective diameter of the pulley 13 is decreased thereby causing the speed of the pulley 21 to be proportionately decreased. The ratio of difference is such as to introduce a substantial 2-to-1 change whereby the speed of rotation of the spindle 22 may be brought down to approximately 400 R. P. M.

Machines of the character described are used both for grinding and polishing lenses and are particularly adapted for use in roughing out strong curved blanks to the approximate shape desired. This is accomplished with the use of a coarse abrasive manually fed on to the lap while the blank is being manually rocked by proper manipulation of the lever 67.

It has been found in the past that difficulty has been encountered in rocking strong convex curves to the approximate shape desired in that the lens and holder jump off the lap particularly when a steep concave tool is being used and if the speed of the rotation of the tool is too great. This difficulty is mostly encountered at the start of the generation of the steep curve in that the lens blank tends to grab the lap and it is difficult to manually hold the lens on the lap even with controlled pressure being applied on the hand lever 67. The present machine therefore, provides an initial relatively slow rotation of the lap which speed of rotation can be increased as the excess material has been ground off the blank and the blank becomes more positively seated to the shape of the curve being generated. This initial slow speed greatly reduces the difficulty in maintaining the blank in abrading relation with the lap and the subsequent increase in speed of rotation of the lap enables the reducing of the grinding cycle. The increased speed is furthermore desirable for 20 polishing.

It is further pointed out that the change in the speeds of rotation of the spindle 22 is brought about by changing the distance between the drive shaft 12 of the motor and said spindle 22. When this change takes place, the 25 spindle 22, base plate 32, housing 49, abrasive pan 53, and the manually operable lever 67, together with its associated parts, all move as a unit with respect to the base 6. The opening 36 provides clearance whereby this movement will take place about the pivot 37 with the base 30 plate 32 slidably engaging the slide blocks 33. Due to the fact that the connection of the crank lever 42 with the tie rod 40 and the connection of said tie rod 40 with the block 38 carried by the base plate 32 are of ball-and 35 socket type, this adjustment may be brought about by merely swinging the lever 46 rearwardly or forwardly when the machine is in operation.

From the foregoing description it will be seen that simple, efficient, and economical means have been provided for accomplishing all of the objects and advantages of the 40 invention.

I claim:

A lens surfacing device of the character described adapted to be supported upon a work bench or the like during use thereof, said device comprising an elongated 45 hollow base of shallow depth and having a forwardly and downwardly inclined top wall, said wall at the forward part thereof being of appreciable width and having a relatively large opening therein, a plate overlying said opening and pivotally attached to said base at one side 50 of said opening, bearing means carried by said plate, a spindle rotatably mounted in said bearing means and extending through said opening, said plate and bearing means supporting said spindle in an upwardly and forwardly inclined position, a lap on the upper end of said 55 spindle, a pulley on the lower end of said spindle and enclosed within the forward part of said hollow base, a pan carried by said plate and surrounding said lap and upper part of said spindle, the bottom of said pan being disposed in substantially parallel relation to said top wall so 60 as to cause abrasive material being used by the device to collect in the lower forward portion thereof, a manually operable lever universally pivotally connected at its rear end to supporting means secured to said base, and extending forwardly across the top of said pan to a location above the forward portion of said base, said lever 65 having a hand grip at its forward end and carrying depending means intermediate its opposite ends for retaining a lens blank in operative engagement with said lap, a motor carried by a rear part of said base and having its drive shaft extending downwardly through a smaller opening in said top wall, said drive shaft being disposed in substantially parallel relation to said rotatable spindle, a drive pulley on said drive shaft within said hollow base, a drive belt of constant length extending about said drive 70 pulley and said pulley on said spindle, a second manually 75 pulley and said pulley on said spindle, a second manually

operable lever pivotally carried by said base and having link means connected thereto and to said plate at a point spaced from the pivotal connection of said plate to said base so as to allow said second lever to swing said plate relative to said base for varying the distance between said spindle and said drive shaft, one of said pulleys having means connected thereto for varying the effective diameter thereof in response to a change in distance between said spindle and said drive shaft, whereby the speed of rotation of said lap may be selectively varied by movement of said second lever, said hand grip on said first lever having a trigger-like electrical switch positioned thereon for controlling the operation of said motor, and electrical means extending from said switch to said motor for electrically connecting said motor to a source of electrical energy, said first and second manually operable levers being disposed adjacent opposite sides of said pan so as to enable an operator of the device to conven-

iently simultaneously manipulate both of said levers when desired while in front of the device and observing the lens surfacing operation being performed thereby.
